PENCIL SHARPENER

Arthur R. Frederick, Brooklyn, N. Y.

Application June 7, 1937, Serial No. 146,921

4 Claims. (Cl. 120—96)

This invention relates to improvements in pencil sharpeners and more particularly to improvements in pencil sharpeners of the type which comprise rotatable cutting members operated by an inward toothed gear.

It is an object of the present invention to provide means whereby particles of wood and pencil lead will be removed from the pencil after sharpening, thereby minimizing soiling of the hands of the user.

Another object of the present invention is to provide means whereby this effect may be obtained in one operation without necessitating separate sharpening and cleaning of the pencil.

Another feature of the present invention is that the cleaning means can be interchanged or entirely removed if desired without interfering with the operation of the sharpener.

The invention will be fully and comprehensively understood from a consideration of the following detailed description when read in connection with the accompanying drawing which form part of the application.

In the drawing:

Fig. 1 represents a vertical section of the apparatus,

Fig. 2 represents a side view of the guard casing used in conjunction with the device according to the present invention, and

Fig. 3 represents a vertical section along the line 3—3 of Fig. 1 with parts removed for clearness.

In the drawing, 4 is a shaft rotatable within the casing member 5, having attached thereto the outer casing member 6 and the fixed internally toothed gear member 7. 8 is a head member fixedly attached to the shaft 4 and carrying the spindles 9 and 10 engaged therein by the threads generally designated at 11 and 12. The members 13 and 14 are rotatable about the spindles 9 and 10 and carry helically ground cutting surfaces designed to engage with pencil 15 and sharpen same in the usual way. A portion of the members 13 and 14 is cut to form spur gears 16 and 17 which engage with the internally toothed gear member 7 fixedly positioned in the casing so that when the shaft 4 is rotated the members 13 and 14 will rotate about their spindles 9 and 10. The sleeve members 18 and 19 are positioned upon an extension collar of the members 13 and 14 and fixed in position upon same by the set screws 20 and 21 so that these collars rotate in conjunction with the cutting members but can be removed from same by loosening of the set screws. The brushes gener-

ally designated at 22 and 23 are fixed within the collars 18 and 19 and the length of the bristles is adjusted so as to form an annular brushing member whose outer radius is substantially equal to the distance between the center point of the 5 spindle as shown in section in Fig. 3 and the axis of rotation of the shaft 4. In this manner it will be evident that the entire pencil and tip will be brushed upon removal from the sharpener. The head member 24 is positioned as 10 shown in Fig. 1 upon the spindles 9 and 10, thereby maintaining the members 13 and 14 and their cooperating members in operable position on their spindles. This member also serves as a guiding means for the pencil and insures that 15 the pencil will be maintained in a position relatively coaxial to the driving shaft 4.

In the preferred embodiment of the present invention the heads 8 and 24 are integrally united, preferably being formed in one piece as 20 shown in Fig. 3. The surfaces 25 of this member serve to assist in guiding the pencil into the desired position between the cutting edges of the helical cutters hereinbefore described. In practice they fit down snugly between these cutters 25 and also serve the additional function of assisting in removal of cuttings from the cutting surface. The shoulders 26 also serve to spring the bristles of the brushes as they are rotated, thereby facilitating cleaning of same. 30

When it is desirable to remove the brushes, as for example for replacement, the outer casing is removed and the threaded spindles 9 and 10 are unscrewed from their seat in the head 8, pulled out, and the helical cutting members with 35 their cooperating parts removed. The collars carrying the brushes can be removed from the cutting members by loosening the set screws as hereinabove mentioned.

It is to be understood that this improvement 40 is capable of extended application and is not confined to the exact showing of the drawing nor to the precise construction described and, therefore, such changes and modifications may be made therein as do not affect the spirit of the 45 invention nor exceed the scope thereof as expressed in the appended claims.

What is claimed as new is:

1. In a device for sharpening pencils, comprising a rotatable shaft carrying a head bearing 50 spindles upon which are mounted helically ground rotatable cutters, the improvement which comprises brush members affixed to said cutters and rotatable in conjunction therewith.

2. In a device for sharpening pencils, compris- 55

ing a rotatable shaft carrying a head bearing spindles upon which are mounted helically ground rotatable cutters, the improvement which comprises brush members affixed to said cutters and rotatable in conjunction therewith, whereby the pencil is brushed as it is removed from contact with the cutting members.

3. In a device for sharpening pencils, comprising a rotatable shaft carrying a head bearing spindles upon which are mounted helically ground rotatable cutters, the improvement which comprises brushing means associated with and

rotatable in conjunction with said cutters and said head, adapted to remove cuttings from objects placed in contact with said cutters.

4. In a device for sharpening pencils, comprising a rotatable shaft carrying a head bearing spindles upon which are mounted helically ground rotatable cutters, the improvement which comprises brush elements mounted on parts of and rotatable in conjunction with said cutters and said head, adapted to remove cuttings from objects placed in contact with said cutters.

ARTHUR R. FREDERICK.
